FISHLINE PACKAGE

Walter J. Hamburger, Dedham, Mass., assignor
to H. Schindler & Co., Inc., Canton, Mass., a
corporation of Massachusetts

Application March 13, 1940, Serial No. 323,685

7 Claims. (Cl. 242—116)

This invention relates to packages for display and storage of fish-lines.

My novel package permits bodily removal of the coil of line therefrom, enabling the purchaser to handle and thoroughly inspect the line before purchase, it permits ready transfer of the line from package to the service reel in the field, and provides a partially collapsible support for the coil whereby pressure of the support against the interior of the coil may be substantially reduced to permit the user to easily remove the coil from the package for storage and use, and to again return it thereto.

The principal object of my invention is to provide a fish-line package which permits removal of the coiled line and return of the line in coil form to the package.

Another object is to provide such a package which permits ready transfer of the line to and from the service reel.

Other objects relate to the construction and mode of operation and will be apparent from a consideration of the following description and accompanying drawing which exemplify one embodiment of my invention chosen for the purpose of illustration.

In the drawing

Fig. 1 is a side elevation of a package embodying my invention;

Fig. 2 is a side elevation showing the opposite side of the package from that shown in Fig. 1;

Fig. 3 is an end elevation of the package of Figs. 1 and 2 with parts broken away and shown in section;

Fig. 4 is a section on the lines 4—4 of Fig. 3;

Fig. 5 is a section similar to that of Fig. 4 but with one of the side members rotated to the position for detachment from the other side member;

Fig. 6 is an enlarged section through a portion of the wall of one side member showing a coil of fish-line in position thereon, the other side member being completely removed and not shown; and

Fig. 7 is an enlarged section similar to that of Fig. 6 but showing a piece of strand material encircling the coil of fish-line and in position for knotting.

The package comprises two relatively flat side members 15 and 16 which are detachably secured together in parallel position.

The inner face of the side member 15 is provided with three outstanding lugs 17. Each of these lugs is provided with a lip or flange 18 at its free end. Semicircular perforations 19

extend transversely through the side member 15 at the respective bases of the lugs 17.

The inner face of the side member 16 is provided with three outstanding lugs 20 and each of these lugs is provided with a lip or flange 21 extending outwardly at its free end (Figs. 2, 3, 6 and 7). Transverse perforations 22 are provided in the side member 16 at the respective bases of the lugs 20. Circular perforations 25 extend transversely through the side member 16. Transverse slots 23 are provided in the side member 16 and the width of each slot gradually decreases as the slot extends away from the base of the respective adjacent lug 20. Each slot 23 at its end adjacent the lug 20 is wide enough to permit the free end and flange of a lug 17 to pass therethrough (see Fig. 5). As the side member 15 and its attached lugs 17 are rotated clockwise (looking at Fig. 5) with respect to the side member 16 to the position shown in Fig. 4 the lugs 17 slide along the slots 23 to the narrower extremities thereof. In that position the flanges 18 of the lugs 17 overlap the edges of the slots 23 and releasably retain the two side members 15 and 16 in parallel position (see Figs. 2, 3 and 4). In that position portions of the lugs 17 preferably frictionally engage the sides of the slots 23 (see Fig. 3) so that manual pressure is required to rotate the member 15 in counterclockwise direction (looking at Fig. 5) with respect to the member 16. Thus the side members 15 and 16 are normally in the relation shown in Figs. 1, 2, 3 and 4 but for complete separation thereof they are rotated to the position of Fig. 5 where the flanges 18 may freely pass through the slots 23. Three outstanding flanges 30 are provided on the inner face of the side member 16. Each flange extends between the bases of adjacent lugs 20, and is located just outside of the outer edges of the slots 23 (Figs. 4 and 5). Perforations 31 extend transversely through the side members 15 and 16 at their respective centers. A handle 33 is secured to the side member 15 by any suitable means.

I prefer to make the entire package of transparent material, such as cellulose acetate, "Lucite" or "Tenite" but any substantially rigid material may be used. If "Lucite" or "Tenite" is used, the package may be molded in three pieces, the handle and the two side members each with its respective lugs integral therewith.

In use, the coil of fly line is placed on the lugs 20 and the side member 15 is assembled with the side member 16 by inserting the ends of the

lugs 17 through the slots 23 and rotating them to the closed position shown in Fig. 4. The purchaser may remove the coil of line for inspection by merely rotating the side member to the position of Fig. 5, separating the side members and lifting the coil over the ends of the lugs 20.

To transfer the line from the package to the service reel, a pencil, stick or the like is inserted loosely through the central perforations 31 and the ends of the pencil are then supported between the knees of the fisherman. The package is then free to rotate about the pencil as an axis and the line is wound directly from the package to the service reel.

To return the line from the service reel to the package I prefer to first place three pieces of strand material 40, such as common string, one piece respectively through each of the holes 25, and to detachably knot each string around the adjacent edge of the side member 16 as shown in Fig. 6. The assembled package is then supported upon any convenient member loosely inserted through the central perforations 31 and using the handle 33 the package is rotated about the inserted member as an axis and the line is wound directly from the service reel to the outer faces of the lugs 17 and 20. In such position the coil of line will be in relatively taut condition, the interior of the coil being supported by the six lugs 17 and 20 which are each spaced substantially an equal distance from the two adjacent lugs as shown in Fig. 4. The side member 15 is then rotated to the position shown in Fig. 5 where the lugs 17 are in collapsed position and all tension of the interior of the coil of line is released, said coil then being supported only by the three lugs 20. The lugs 17 may then be withdrawn from the slots 23 and the side member 15 removed from the package. The flanges 21 on the ends of the lugs 20 serve to prevent the coil from slipping over the ends of the lugs 20 while the lugs 17 are withdrawn from the slots 23. The coil is then preferably secured in coil form by the three strings 40. This is done by untying each string 40 and pulling the lower end (Fig. 6) through the hole 25 (Fig. 6) so that the string encircles the coil and may be knotted as shown in Fig. 7. The coil is then encircled by pieces of string at three spaced points corresponding to the holes 25.

The coil may then be easily removed from the lugs 20 since all tautness or tension of the line was released when the lugs 17 were rotated to collapsed position. The coil may be removed for storage and later slipped over the ends of the lugs 20 and the package reassembled for retransfer of the line to the service reel. The package may be used to remove different lines from the service reel since it permits bodily removal of each coil from the lugs and bodily return thereto.

The function of the flanges 30 is to retard any tendency of the line to enter the slots 23 when the lugs 17 are inserted therein with a coil of line in place on the lugs 20.

The perforations 19, 22, 25 and 31 also serve to admit air and to ventilate the line when it is in place on the lugs 17 and 20.

It is to be understood that this disclosure is for the purpose of illustration and that various changes in shape, proportion and arrangement of parts and the substitution of equivalent elements may be made without departing from the spirit and scope of the invention as set forth in the appended claims.

I claim:

1. A fish-line package comprising a relatively flat side member, a plurality of outstanding members secured to one face thereof, a slot in said side member extending from adjacent the base of one of said outstanding members, a second relatively flat side member and an outstanding member secured to one face of said second side member and having an end portion adapted to slide longitudinally of said slot.

2. A fish-line package comprising a relatively flat side member, a plurality of outstanding members secured to one face thereof, a slot in said side member extending from adjacent the base of one of said outstanding members and having a restricted portion spaced from the base of said outstanding member, a second side member and an outstanding member secured to one face of said second side member and having an end portion adapted to enter the wider portion of said slot and to slide longitudinally of said slot into the restricted portion thereof.

3. A fish-line package comprising a relatively flat side member, a plurality of outstanding members secured to one face thereof, a slot in said side member extending from adjacent the base of one of said outstanding members and having a restricted portion spaced from the base of said outstanding member, a second relatively flat side member and an outstanding member secured to one face of said second side member and having a flange adjacent its free end, said flanged end of said latter outstanding member being adapted to enter the wider portion of said slot and said latter outstanding member being slidable longitudinally of said slot into the restricted portion thereof where said flange is engageable with a portion of said first side member.

4. A fish-line package comprising a relatively flat side member, a plurality of outstanding members secured to one face thereof, a plurality of slots in said side member extending respectively from adjacent the bases of said outstanding members, a second relatively flat side member and a plurality of outstanding members secured to one face of said second side member and each having an end portion adapted to slide longitudinally of one of said slots.

5. A fish-line package comprising a relatively flat side member, a plurality of outstanding members secured to one face thereof, a plurality of slots in said side member extending respectively from adjacent the bases of said outstanding members and each slot having a restricted portion spaced from the base of the adjacent outstanding member, a second relatively flat side member and a plurality of outstanding members secured to one face of said second side member, each having an end portion adapted to enter the wider portion of one of said slots and to slide longitudinally of said slot into the restricted portion thereof.

6. A fish-line package comprising a relatively flat side member, a plurality of outstanding members secured to one face thereof, a plurality of slots in said side member extending respectively from adjacent the bases of said outstanding members, a second relatively flat side member and a plurality of outstanding members secured to one face of said second side member each having a flange adjacent its free end, each of said flanged ends of said latter outstanding members being adapted to enter the wider portion of one of said slots and said outstanding members being slidable longitudinally of said slots.

into the restricted portions thereof where said flanges are engageable with a portion of said first side member.

7. A fish-line package comprising a relatively flat side member, a first outstanding member fixed to one face thereof, a slot in said side member extending from adjacent the base of said outstanding member, a second relatively flat

5 side member spaced from the first side member substantially parallel thereto and located adjacent the end of said first outstanding member, a second outstanding member secured to one side of said second side member and having an end portion adapted to slide longitudinally of said slot.

WALTER J. HAMBURGER.
